CLAIM

The ornamental design for a light-emitting diode package, as shown and described.

DESCRIPTION

FIG. 1 is a top perspective view of the light-emitting diode package;

FIG. 2 is a bottom perspective view of the light-emitting diode package of FIG. 1;

FIG. 3 is a top view of the light-emitting diode package of FIG. 1;

FIG. 4 is a bottom view of the light-emitting diode package of FIG. 1;

FIG. 5 is an end view of the light-emitting diode package of FIG. 1;

FIG. 6 is an opposing end view of the light-emitting diode package of FIG. 1;

FIG. 7 is a side view of the light-emitting diode package of FIG. 1; and,

FIG. 8 is an opposing side view of the light-emitting diode package of FIG. 1.

The broken lines shown in the drawings depict portions of the light-emitting diode package that form no part of the claimed design.
